UNITED STATES PATENT OFFICE.

DENTON SIMPSON, OF CENTRE, INDIANA.

CORN-PLANTER.

SPECIFICATION forming part of Letters Patent No. 634,482, dated October 10, 1899.

Application filed June 5, 1899. Serial No. 719,468. (No model.)

To all whom it may concern:

Be it known that I, DENTON SIMPSON, a citizen of the United States, residing at Centre, in the county of Howard and State of Indiana, have invented a new and useful Corn-Planter, of which the following is a specification.

This invention relates to corn-planters, and more especially to the seed-dropping mechanism thereof; and it has for its object to provide a new and useful construction of seed-dropping mechanism having simple and efficient means for positively dropping the seed through the seed spout or tube without injury thereto.

With this and other objects in view, which will readily appear as the nature of the invention is better understood, the same consists in the novel construction, combination, and arrangement of parts hereinafter more fully described, illustrated, and claimed.

While the essential features of the invention are necessarily susceptible to modifications without departing from the spirit or scope thereof, still the preferred embodiment of the same is shown in the accompanying drawings, in which—

Figure 1 is a front elevation of a portion of the runner-frame of a corn-planter, showing the applied position of the actuating devices for the dropper or dropping mechanism contemplated by the present invention. Fig. 2 is a detail in perspective of a seed-dropper constructed in accordance with the present invention. Fig. 3 is a vertical sectional view of the dropping mechanism in its applied position. Fig. 4 is a transverse sectional view on the line $x-x$ of Fig. 3. Fig. 5 is a horizontal sectional view on the line $5-5$ of Fig. 4. Fig. 6 is a detail plan view of the actuating-drum which is preferably associated with each dropping-wheel.

Like numerals of reference designate corresponding parts in the several figures of the drawings.

Referring to the accompanying drawings, the numeral 1 designates a portion of the runner-frame of an ordinary corn-planter having the usual runners or openers 2 and the seed tubes or spouts 3, which are in communication with the seedboxes or hoppers 4, located at opposite sides of the runner-frame

in the usual way, and the seed-dropping mechanism arranged within the seedboxes or hoppers 4 is designed to be operated from 55 the ordinary reciprocating dropper-actuating bar 5, which bar is reciprocated by any well-known check-row or other operating mechanism which is usually provided for this purpose. However, said mechanism forms no 60 part of the present invention and is not shown in the drawings. The droppers or dropping mechanism associated with each of the opposite seedboxes or hoppers 4 are duplicates in construction, so that a description of one 65 will suffice for the other.

Referring particularly to Fig. 3 of the drawings, it will be observed that the bottom of each seedbox is provided with a wheel-opening 6, disposed transversely of the planter-frame and receiving therein the fixed or stationary delivery-head 7, preferably in the form of a disk or circular block and provided therein with a vertical diametric seed-opening 8, having flared end portions communicating, respectively, with the interior of the seedbox 4 and the delivery tube or spout 3. The stationary or fixed delivery-disk 7 loosely receives thereon a hollow oscillatory dropping-wheel 9, working loosely within the 80 wheel-opening 6 and essentially comprising the opposite circular heads 10 and a rim 11, interposed between said heads and secured to the peripheral edges thereof to complete the hollow wheel, which registers upon the 85 disk 7 and at the same time permits of the passage of seed therethrough. The rim 11 of the oscillatory dropping-wheel is provided in the lower side thereof with an elongated discharge opening or slot 12 in communication 90 with the lower end of the seed-opening 8, and in its upper side the rim 11 of the dropper-wheel is provided with smaller-spaced feed-openings 13, adapted to be alternately thrown into communication with the upper end of the 95 seed-opening 8 through the disk or wheel 7. It will be noted that the bottom discharge opening or slot 12 is sufficiently long to uncover the lower end of the seed-opening 8 in all positions of the dropping-wheel. In order to permit the dropping-wheel to turn freely and independently of the stationary disk or head 7, the said wheel has projected centrally from the opposite heads or sides

thereof the diametrically opposite spindles 14, which turn in bearings formed at opposite sides of the opening 6, as plainly shown in Fig. 4 of the drawings, and to properly secure the disk or head 7 against axial movement the said disk has fitted therein a pair of supporting-pins 15, arranged at diametrically opposite sides of the center of the disk or head and having their standards fitting in the bottom of the seedboxes at opposite sides of the wheel-opening 6. To permit of the movement of the dropper-wheel over the supporting-pins 15, the heads or the side portions of the dropping-wheel are each provided with a pair of oppositely-located and reversely-arranged arcuate slots 16, which receive the said pins 15. In this connection it will be observed that the pins 15 not only provide for properly supporting the disk or head 7 in place, but also act in the capacity of stop-pins to stop or limit the oscillation of the dropping-wheel in both directions.

Each dropping-wheel 9 is preferably operated from and in unison with an actuating-drum 17, journaled in suitable supports 18, exterior and adjacent to the seedboxes at the inner side thereof, as shown in Fig. 1 of the drawings. The oppositely-arranged actuating-drums 17 have extended therefrom a fixed arm or lever 19, connected, respectively, with the opposite ends of the reciprocating dropper-actuating bar 5, so that when the usual check-row or other operating mechanism for the bar 5 transfers motion to said bar said bar will in turn simultaneously oscillate the oppositely-located drums 17, which will in turn transfer an oscillatory motion to their respective dropping-wheels through the medium of the operating-wires 21 or other equivalent flexible connections 22, respectively. The operating-wires or equivalent flexible connections 21 and 22 are respectively arranged at the upper and lower sides of each dropping-wheel and its actuating-drum 17, it being noted that the upper operating-wire 21 passes over the upper side of the actuating-drum 17 and also passes over the upper side of the dropping-wheel, while the lower operating-wire 22 is arranged in reverse relation, although both of the operating-wires are fastened at their extremities respectively to the dropping-wheel and its actuating-drum. By reason of thus connecting the operating-wires with each dropping-wheel and its actuating-drum a positive oscillation will be imparted to the dropping-wheel when its actuating-drum oscillates in either direction. To provide for properly retaining the operating-wires 21 and 22 upon each dropping-wheel and its actuating-drum and thereby preventing lateral displacement of the wires, each dropping-wheel and its actuating-drum is preferably provided with a pair of peripheral retaining-grooves 24 and 25, located, respectively, at the opposite side edges of the wheel, as plainly shown in Figs. 2 and 6 of the drawings.

Arranged within each of the seedboxes is an arched guard or shield 26, extending over the upper side of the dropping-wheel and provided with flanged ends 27, secured upon the rim of the box. At its flanged ends the arched shield 26 is provided with openings 28 in communication with seed-notches 29, formed at opposite ends of the wheel-opening 6 to facilitate the passage of seed into the feed-openings 13 of the dropping-wheel, which construction may be plainly seen from Fig. 3 of the drawings. In the operation of the machine through the medium of the connections described the dropping-wheels are oscillated so as to alternately bring their separate feed-openings 13 in register with the opposite seed-notches 29, so that said notches will receive or take up the seed and elevate the same to the upper end of the seed-opening 8, through which and the discharge opening or slot 12 the seed falls into the seed-delivery tube or spout 3. As the shield or guard completely incloses the dropping-wheel, the seed has access to the pockets 13 therein only through the comparatively small opening 28, formed in the shield, and the seed is directed into said pockets through the downwardly-inclined notches 29 in a manner to prevent catching and consequent breaking or damage of the seed. It will be seen that the peripheral edge of the fixed disk 7 provides a bottom for the pockets 13 until the latter are alined with the vertical opening 8 in the disk, when the seed is free to drop through the same.

Changes in the form, proportion, size, and the minor details of construction within the scope of the appended claims may be resorted to without departing from the spirit or sacrificing any of the advantages of this invention.

What I claim is—

1. In a seed-dropper for planters, the combination with a seedbox having a bottom opening, of a stationary disk supported within said opening and having a seed-opening extending therethrough, and a hollow oscillatory dropping-wheel loosely working over and completely housing therein the stationary disk, and provided in its lower side with an elongated discharge-slot and in the upper side with a pair of spaced feed-openings, said dropping-wheel having the inclosing side portions thereof engaged with suitable stops to limit the oscillation thereof, substantially as set forth.

2. In a seed-dropper for planters, the combination with a seedbox having a bottom opening, of an oscillatory dropping-wheel supported within said opening, an oscillatory actuating-drum supported exteriorly of the seedbox, means for oscillating the said drum, and flexible operating connections between the drum and the dropping-wheel, substantially as set forth.

3. In a seed-dropper for planters, the combination with a seedbox, of an oscillatory dropping-wheel supported within the bottom

of the seedbox, an oscillatory actuating-drum supported exteriorly of the seedbox, a pair of upper and lower flexible operating connections arranged in reverse relation and connected respectively with the periphery of the dropping-wheel and its actuating-drum, and means for oscillating said drum, substantially as set forth.

4. In a seed-dropper for planters, the combination with a seedbox having a bottom discharge-opening, and provided at the ends of said opening with seed-notches, of a drop-

ping-wheel within said opening, and an arched guard arranged within the box over the dropping-wheel, and provided at its ends with 15 openings in communication with said seed-notches, substantially as set forth.

In testimony that I claim the foregoing as my own I have hereto affixed my signature in the presence of two witnesses.

DENTON SIMPSON.
